DESIGN FOR A COMBINATION TUMBLER AND TOOTHBRUSH HOLDER

Roy S. Sanford, Oakville, Conn., assignor to
The Autoyre Company, Incorporated, Oakville,
Conn., a corporation of Connecticut

Application October 12, 1940, Serial No. 95,794

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Combination Tumbler and Toothbrush Holder, of which the following is a specification, reference being had to the accompanying drawing, forming a part thereof.

Figure 1 is a perspective view of the combination tumbler and toothbrush holder incorporating the features of my new design; and

Fig. 2 is a top plan view of Fig. 1.

I claim:

The ornamental design for a combination tumbler and toothbrush holder, substantially as shown.

ROY S. SANFORD.
